JACOB GROSSMAN, OF MASPETH, NEW YORK

BOX

Application filed May 23, 1928. Serial No. 280,087.

My invention relates to folding boxes, and more particularly to a box having a carrying handle formed with the material of which the box is composed, and which will serve not only as a means for carrying the box, but also as means to keep the box in closed condition while being carried. The present box is suitable for carrying cloaks, suits and various garments, and it is, therefore, adapted for containers in which such articles may be sold by merchants to customers carrying their purchases with them.

The present device comprises a box having a body and a co-operating member which may be considered as a cover, the body and cover preferably being made from a single sheet of cardboard, suitably scored or creased, and blanked. The blank is adapted to be folded and assembled with suitable locks; and the handle portion, which is of double-thickness, is formed from the material of which certain walls of the box are formed, so that the complete box with the handle requires no greater material than would ordinarily be required for the making of a plain box. The handle portion may remain flat before the blank is folded, and it may be readily turned up into position and passed through a slot in the cover member, so that the body and cover are retained in closed position by the handle.

In the drawings forming part of this application,

Figure 1 is a face view of a blank, suitably cut and scored or creased and from which the improved box is to be made,

Figure 2 is a sectional view through the center of the box when assembled and ready for carrying,

Figure 3 is a perspective view of the box when folded and assembled and ready to be closed for carrying,

Figure 4 is an end view of the box in closed position,

Figure 5 is a sectional view on an enlarged scale, taken on the line 5-5 of Figure 3, and

Figure 6 is an end view of the box looking at the right hand end of Figure 5.

While various changes may be made in

the blank from which the box is formed, I have shown in Figure 1 the preferred form of blank to be used in assembling a box containing my invention. In this view the blank 1 has a section 2 which is to form the top wall of the cover member, this portion being defined by the four scoring or creasing lines 3, 4, 5, 6. The portion 7 which is outside of one of the crease lines, 4, is to form one of the side walls of the cover; and the opposite portion 8 outside of the crease line 6 is to form another side wall of the cover. The portion 9 which is outside of the crease line 3 is to form one end wall of the cover; and the portion 10 outside of the crease line 5 is to form the opposite end wall of the cover. At the four corners of the cover portion of the blank I have shown suitable tabs 11, 12 which are adapted to be inserted into the several diagonal slots 13, 14 for the purpose of forming locks between the side and end walls when the latter are folded in relation to the section 2 when the box is being set up from the blank.

The other half of the blank 1, which is to form the body of the box, comprises a section 15 which is outlined by the crease lines 16, 17, 18, 19 and is to form the bottom wall of the box body. The portion 20 outside of the crease line 17 is to form one of the side walls of the body; and the portion 21 outside of the crease line 19 is to form the opposite side of the body.

The member 10 forms a wall at one end 85 of the box which is common to both the cover and the body. The portion of the blank which is outside of the crease line 18 is of a width corresponding preferably with twice 90 the depth of the box and it is provided with a crease line 22 approximately halfway between the crease line 18 and the end of the blank, so that the portion 23 may be folded over against the portion 24 before this folded portion is turned up to constitute the end wall of the body. Tabs 25 are provided at each side of the portion 24 which are adapted 95 to be inserted into the oblique slots 26 on the members 20, 21 to provide locks for se- 100

curing the end and side walls of the body member.

The novel handle which forms the subject of my invention is shown in the upper part 5 of Figure 1. The crease line 22 extends across the blank, and therefore extends across the middle of the section which is to form the handle. The sections 27, 28 are cut out as shown at 29 to form a double outline of the handle and creases are formed at the four lines 30 on which the intermediate sections 27, 28 which are to form the handle, may be bent. In addition, in the preferred construction, there are two angular cuts 31, made 10 at four interior corners of the handle section, and in triangular relation therewith there are formed four crease lines 32.

In assembling or forming the box no definite order of procedure is necessarily followed, but I will describe one method of 20 forming the blank into a box. The cover section of the blank 1 will be folded along the crease lines 4, 6 so that the two sections 7, 6 which are to form the side walls will be 25 bent upwardly at right angles to the top wall section 2; and the end section 9 will be bent up along the crease line 3 and the opposite end section 10 will be bent up along the crease line 5, so that all of the four members 9, 7, 30 10, 6 stand at right angles to the section 2.

The various tabs 11, 12 will then each be inserted into their respective slots 13, 14 and 35 form a lock at each of the four corners of the cover section (as shown in Figure 3). This completes the formation of the cover section. It will be noted that there is a longitudinally extending slot 34 in the end wall section 9 of the cover member, the purpose of which will be set forth. The body portion may 40 now be assembled by bending up the two side portions 20, 21 along the crease lines 17, 19. The end section is then folded on the crease line 22 so that the portion 23 is superimposed upon the portion 24 and this also folds the 45 portion of the blank which constitutes the handle, across its central line 22. The blank is then bent upon the crease line 18 so that the doubled end wall is bent up at right angles to the section 15. The tabs 25 are now inserted 50 into their respective slots 26 so that end locks are provided at two of the corners of the body.

To close the box the cover is hinged by bending it along the crease line 16, as shown 55 in Figure 3, so that the side and end walls of the cover overlap the side walls and the end wall of the body. The folded handle members 27, 28 which now comprise two thicknesses of cardboard, are bent upwardly 60 along the crease lines 30, so that as the end wall 9 of the cover slides over the end wall 23, 24 of the body the handle is turned outwardly through the slot 34 in the end wall of the cover; and when the cover has been completely 65 closed the handle may be bent up-

wardly as shown in Figures 2 and 4. After the handle has been brought to this position the triangular extensions 35 may be turned at right angles to the plane of the handle to prevent the handle withdrawing through the slot 70 34 in the cover, thereby preventing the box 70 from accidentally opening.

The handle forms a convenient means for carrying the box and at the same time it retains it in closed condition. The handle being composed of two thicknesses of cardboard it is sufficiently strong to support the box and its contents. The strain on the carrying handle comes directly on the end wall of the body which is of double thickness and also on the end wall of the cover, so that the box is amply able to resist tearing when carrying its greatest load.

It will be obvious that the box blanks 1, as shown in Figure 1, may be shipped in 85 knock-down or flat form to merchants, and they may be stored or kept in this condition so that they occupy a minimum of space until they are to be formed into boxes. The forming of the blank into a box is very simple 90 and may be done as quickly as with an ordinary folding box. The handle is formed from the same material of which the end wall of the body is formed, so that no stock is wasted in the formation of the handle.

Having described my invention, what I claim is:

1. A folding box formed of a blank and having a bottom wall and side and end walls, one of said latter walls comprising a section 100 folded upon itself to provide a wall of double thickness and a handle member formed in said section of duplicate, reversely arranged parts, each of said handle parts being formed on one of the folded portions of said double wall, whereby when said wall is folded upon itself the handle member may be bent upwardly therefrom and form a handle composed of a double thickness of the blank material.

2. A folding box formed of a blank having a bottom wall and side and end walls, one of said latter walls comprising a section having a crease or score line extending across the same, a handle member formed by cutting 115 said section to form similar handle members on opposite sides of said crease or score line, said section being adapted to be folded upon itself to provide a wall of double thickness and said handle sections being adapted to be 120 folded on a line coinciding with said first mentioned crease or score line, whereby a handle of double thickness will be formed on said wall.

3. A folding box formed of a blank having 125 a bottom wall and side and end walls and having a section connected with the body section and adapted to form a cover for closing said body section, said cover member having a slot therein, said body member having a sec- 130

- tion foldable on itself to provide a wall of double thickness, and a handle member formed of said latter section and comprising similar parts reversely arranged in relation to each other and foldable with said section whereby a handle of double thickness is formed in said wall of double thickness, said handle being adapted to be projected through the slot in said cover member.
4. A folding box formed of a blank having a bottom wall and side and end walls, one of said latter walls comprising a section adapted to be folded upon itself to form a wall of double thickness, a handle member comprising similar, relatively reversely disposed sections formed from said double wall to provide a handle of double thickness, a cover member having a slot to receive said handle therethrough, and tabs projecting from said handle member and adapted to be bent at an angle thereto after said handle member has been passed through said slot in the cover, whereby to prevent the withdrawal of the handle member from said cover member.

Signed at the city, county, and State of New York, the 23rd day of April, 1928.

JACOB GROSSMAN.
